UNITED STATES PATENT OFFICE

1,936,413

SPRAY NOZZLE

George H. Stillson, Crockett, Calif.

Application November 25, 1930
Serial No. 498,033

4 Claims. (Cl. 210—67)

My present invention relates to centrifugals such as are used for washing sugar and the like and more particularly to an improved spray nozzle for directing the wash water against the 5 walls of the centrifugal in a uniform manner.

The principal object of my invention is to provide a new and novel spray nozzle for centrifugal washing machines which will distribute a spray of wash water from a central point to the walls 10 of the centrifugal in uniform amounts irrespective of the distance from the nozzle of the surface to be washer.

A further object of my invention is to provide in a nozzle of the above character a means where- 15 by the direction of the spray with respect to the axis of a centrifugal may be changed without disturbing the location or position of the nozzle proper.

Other objects and advantages of my invention 20 will be in part pointed out and in part evident from the following description taken in connection with the accompanying drawing wherein I have shown, by way of illustration and not of limitation, a preferred form of my invention.

25 In the drawing wherein like numerals refer to like parts throughout the several views;

Figure 1 is a vertical sectional view taken centrally through a centrifugal showing the disposition of the spray nozzle with respect to the 30 sugar or other material to be washed.

Figure 2 is a side view of my improved nozzle showing the spray forming orifice,

Figure 3 is a vertical sectional view taken along the center of the nozzle, and

35 Figure 4 is a horizontal sectional view taken along line IV—IV of Figure 3.

In describing my invention I shall refer to it as applied to a sugar washing centrifugal but I desire to have it understood that my invention 40 is also adapted to centrifugals for washing other materials where it is desirable that the whole surface of the material being washed must be subjected to a uniform amount of wash water.

45 In the washing of sugar crystals at the refinery the crystallized sugar as taken from the evaporating pans contains a certain amount of uncrystallized juice which must be separated from the crystals. This operation is carried out by placing the sugar masscuite in a basket type 50 of perforated receptacle that is rotated at a high speed about a vertical axis and in which the sugar, as it is disposed around the wall of the basket by centrifugal force, is subjected to a high velocity jet or spray of washing water.

55 For a proper washing of the sugar crystals in

this manner it is necessary that the washing operation be timed so that the crystals will not be subjected to more water than is required for the elimination of the impurities. It is also necessary that the spray or jet from the nozzle be so 60 directed that the layer of crystals disposed upon the walls of the basket will be subjected to a uniform amount of wash water over the entire surface during the washing operation.

When the sugar is disposed within the centrifugal as suggested above it will be seen that the surfaces of the sugar above and below the spray orifice of the nozzle will be farther from the nozzle orifice than the surface directly adjacent the nozzle. As a result of this variation in the distances 65 to different parts of the sugar wall and the resultant variations in the angles of contact of spray with the sugar wall, the distribution of washing water will be uneven with a nozzle having an orifice of uniform width. 75

In order to overcome the above and provide for a uniform amount of wash water at the surface of the sugar being washed, I propose to so proportion the spray orifice that the amount of water passing therethrough at any point will be 80 substantially proportional to the distance of the orifice to the surface being washed thereby.

As shown in Figure 1 of the drawing, my improved nozzle designated by the numeral 10 is mounted upon the end of a pipe 11 and is disposed slightly above the horizontal center of a centrifugal 12 in which a quantity of sugar 13 to be washed is disposed. The centrifugal 12 may be of any desired type. As here shown it consists of a perforated basket suspended upon a vertical shaft 14 by means of which it is rotated. Surrounding the centrifugal 12 there is also provided the customary apron or housing 15. 85

As illustrated in Figure 2, my improved nozzle 10 comprises a body portion 16 having a threaded 95 end for mounting it upon the pipe 11, and a cap portion 17 which cooperates therewith to form an orifice 18.

By referring to Figure 3, it will be seen that the member 16 and the cap 17 are secured together by a centrally disposed bolt 18' so that the cap 17 can be rotated therearound. The portion 16 is provided with a suitable valve seat 19 against which a valve 20 is retained by a suitable spring 21. At the point where the bolt 18' 100 is threaded into the member 16, I provide a plurality of openings 22 through which the wash water may enter a cavity 23 formed by recesses 24 and 25 formed respectively in the member 16 105 and the cap 17. In providing the recesses 24 and 110

25 in the member 16 and the cap 17 it will be seen that annular surfaces will be formed upon these parts which will surround and form a wall about the cavity 23.

5 In order to provide the spray forming orifice 18, I show the cap 17 as machined or filed away as at 26, so that the annular surfaces surrounding the cavity 23 will not meet at this point. In machining the cap 17 at the point 26, I cut away the

10 metal so as to form an annular slot having what might be termed an hour glass shape, or in other words, a slot having a varying width throughout its length, it being wider at the extreme ends than at its center.

15 An orifice for nozzles spraying approximately 7 gallons of water per minute which will give good results is one having an arcuate length of approximately $2\frac{1}{4}$ " and the following widths; at the top .022", at the point nearest the sugar wall .016", and at the bottom .074". Such an orifice will give a uniform distribution of washing water to all parts of the sugar wall and will require less water than other types.

20 In practice the nozzle 10 is disposed above the horizontal center of the basket and about 14" from the sugar wall at the point level with the nozzle. With the nozzle so disposed, the distance to the top of the wall of sugar from the nozzle will be approximately $16\frac{1}{2}$ " and the distance to the bottom of the sugar wall will be approximately 30".

25 As the water leaves the orifice 18 it will form a fan-like sheet or spray of water which will have a cross section at the nozzle corresponding to the shape of the orifice and as the water travels outwardly it will thin out, particularly at the top and bottom until it strikes the sugar, when it will have a substantially uniform thickness.

30 While I have, for the sake of clearness and in order to disclose my invention so that the same can be readily understood, described and illustrated specific devices and arrangements, I desire to have it understood that this invention is not limited to the specific means disclosed but 35 may be embodied in other ways that will suggest themselves, in view of this broad disclosure, to persons skilled in the art. It is believed that this invention is broadly new and it is desired to claim it as such so that all such changes as come within 40 the scope of the appended claims are to be considered as part of this invention.

Having thus described my invention, what I claim and desire to secure by Letters Patent is:

1. A spray nozzle for sugar washing centrifugals and the like, comprising a body portion adapted to connect with a source of fluid, and an end closure member for said body portion secured

in clamped engagement therewith by a single axially extending screw, said end closure member having a portion cut away to form a discharge orifice between said end closure member and said body portion and being rotatably mounted upon said axially extending screw, whereby said end closure member may be turned to control the direction of the spray without changing the character of the discharge orifice.

2. In a spray nozzle for sugar washing centrifugals and the like, the combination of a body portion forming a fluid conduit adapted to connect with a source of spray fluid and having a vertically disposed annular surface at its discharge end, a closure means having a raised annular surface for engaging said first annular surface, a portion of said raised annular surface being cut away to provide an irregular spray forming orifice, and a stud passing centrally through said latter portion and engaging said body portion for securing said two annular surfaces in abutting engagement, whereby one annular surface can be rotated with respect to the other to vary the direction of the spray formed by the orifice without changing the character of the orifice.

3. In a spray nozzle for sugar washing centrifugals and the like, the combination of a body portion forming a fluid conduit adapted to connect with a source of spray fluid and having a vertically disposed annular surface at its discharge end, a closure means having a raised annular surface for engaging said first annular surface, a portion of said raised annular surface being cut away to provide an irregular spray forming orifice, and means disposed centrally of said annular surfaces for securing them in abutting engagement, whereby one to rotate thereabout to vary the direction of the spray without changing the character of the spray orifice.

4. In a spray nozzle for sugar washing centrifugals and the like, the combination of a body portion forming a fluid conduit adapted to connect with a source of spray fluid and having an annular surface disposed about its discharge end, a closure means having a raised annular surface engaging said first annular surface and forming a fluid cavity, a portion of said raised annular surface being cut away to provide an arcuate spray forming orifice in one side of said cavity having a greater width at its ends than in the center, and means disposed centrally of said annular surfaces for securing them in abutting engagement and permitting one to rotate thereabout to vary the direction of the spray without changing the character of the spray orifice.

GEORGE H. STILLSON.
